2-AMMONIO-ETHYL 3-AMMONIOPROPIONATES

Arthur R. Williams, Berkeley, and John Hidalgo, Richmond, Calif., assignors to Cutter Laboratories, Inc., Berkeley, Calif., a corporation of California

No Drawing. Application June 28, 1954,
Serial No. 439,890

7 Claims. (Cl. 260—482)

This invention relates to organic compounds and is more particularly concerned with a specific group of organic compounds having the following formula:

wherein R and R' are methyl or ethyl, which may be the same or different, and wherein X and X' are stable, non-toxic anions.

It has been proposed recently that in many surgical procedures, it would be exceedingly advantageous to have an agent available which would produce a marked but temporary drop in blood pressure without any other physiological effects, and which would be so short acting that the blood pressure would return to normal within a few minutes after the administration of the agent was stopped. With such an agent available, the surgeon could begin the administration of the drug just before he was required to cut across a venous bed, thus reducing the intensity of the bleeding. While the administration was being continued, the surgeon could apply conventional hemostats, then cease the administration of the drug, and with the immediate rise in blood pressure, observe, by renewed bleeding any bleeding points that were missed. The use of such a drug should markedly reduce the loss of blood during complicated surgery as well as reduce the time of the surgical procedures.

Since this concept was proposed, several hypotensive drugs have been tried but so far all have failed to completely satisfy the requirements.

Alpha-1,3-dibenzyldecahydro-2-oxo-imidazo-[c]thieno-[1,2-a]-thiolium d-camphor sulfonate, known in the art as Arfonad, is a fairly short acting hypotensor, and has been tried, but it requires so near the lethal dose to produce the required lowering of the blood pressure that it is not considered a safe drug for an elective procedure; also, when administration is ceased, six to eight minutes are required for the blood pressure to return to normal. Hexamethonium, one of the most powerful hypotensors, is very effective in lowering the blood pressure. However, its action persists for at least twenty minutes after injection has been stopped and it is therefore completely unsuitable for this purpose. To date, no one has produced a compound which is safe to use and which will cause a controllable drop in blood pressure.

During the course of a general synthetic program, a group of compounds containing two quaternary nitrogen groups separated by four to six carbon atoms and containing one ester group has been prepared which individually shows striking differences physiologically but two of which have proven of value in controlled hypotension.

2-(trimethylammonio)ethyl 3-(trimethylammonio)-propionate diiodide was synthesized and proved to be a very potent and short acting hypotensor, but extremely cholinergic. Among the cholinergic side effects, it pro-

duced an intense salivation which would be dangerous in an anesthetized patient. This compound was described by Fusco et al. (Gass. Chim. Ital. 79, 836-48, 1949) who were searching for drugs with curare-like properties. We also synthesized the corresponding dichloride (M. P. 213-214 degrees) and found its pharmacological properties to be quantitatively the same as those of the diiodide, except that the dichloride was more potent, proportional to its lower molecular weight.

- 10 The compounds which are the subject of this invention, 2-(dimethylethylammonio)ethyl 3-(dimethylethylammonio)propionate dianion and 2-(diethylmethylammonio)ethyl 3-(diethylmethylammonio)propionate dianion, have proven to be extremely potent and short acting hypotensors with a wide margin of safety and little or no cholinergic action. For example, the 2-(dimethylethylammonio)ethyl 3-(dimethylethylammonio)-propionate diiodide, in an intravenous dose of 0.1 milligram per kilogram of body weight causes a rapid fall in 15 blood pressure of 50-60 millimeters of mercury absolute, and the blood pressure returns to normal within 30-60 seconds after administration of the drug is interrupted. The mechanism of the hypotension is apparently by ganglionic blockade. By even rapid injection, salivation, 20 or other cholinergic effects, is not detectable except at a dosage of 0.2 milligram per kilogram. The MLD in mice is 50 milligrams per kilogram, which offers a very wide margin of safety. 2-(diethylmethylammonio)-ethyl 3-(diethylmethylammonio)-propionate diiodide shows no cholinergic activity and is slightly more toxic, 25 the MLD in mice being 37.5 milligrams per kilogram. In other words, they meet the criterion for use in controlled surgical hypotension, and are preferably used in the form of the dichlorides.
- 30 35 Schueler et al. (Science 113, 512-514, 1951) described 2-(triethylammonio)ethyl 3-(triethylammonio)propionate dibromide which meets some of the requirements outlined above; except that its hypotensive action is so weak as to be valueless for use as a controlled surgical 35 hypotensive agent. As pointed out in Schueler's more recent publication (J. Am. Pharm. Assoc., Sci. Ed., 43, 98, 1954), the dose required to produce a significant hypotension even when supplemented by the technic of "postural hypotension" was 4-10 milligrams per kilogram. The corresponding diiodide synthesized by us was found to be an extremely weak hypotensor.

The compounds of the present invention are colorless crystals which are water and methanol-soluble.

Preparation of the compounds of the present invention 50 may be readily accomplished by the interaction of a suitable 2-haloethyl 3-halopropionate and dimethylethylamine or diethylmethylamine, wherein the halogen of the ester is chlorine, bromine, or iodine. The reaction is usually accomplished in the presence of a solvent, such as, for example, chloroform, dioxane, acetone, et cetera, and temperatures between about ten degrees centigrade and 100 degrees centigrade may be employed. The reaction time will be dependent upon the temperature which is used and for reasons of convenience, room temperature is usually employed. When room temperature is employed, the reaction time will be at least one day and preferably about three days, in order that a substantially complete reaction may occur. The reaction product is separated in conventional manner.

65 Alternatively, the compounds of the present invention may be prepared by the quaternization of an appropriate di-tertiary-amino ester. This reaction is accomplished by contacting the free diamino ester with a suitable methyl or ethyl halide, in the presence of a suitable solvent, and recovering the diammonio ester thus prepared.

While both of the above procedures result in the preparation of halide anions, the present invention also con-

templates other stable, non-toxic anions, such as, for example, the nitrate, sulfate, phosphate, acetate, bitartrate, citrate, borate, formate, lactate, oxalate, propionate, et cetera. These anions may be substituted for the halide anion by treatment of the halide-containing material with a salt of the appropriate acid which will form an insoluble halide, or by the use of ion exchange resins in conventional manner.

The following preparations may be used to prepare certain intermediates for the compounds of the present invention.

PREPARATION 1.—2-IODOETHYL 3-IODOPROPIONATE

A solution of twenty grams (0.117 mole) of 2-chloroethyl 3-chloropropionate and 35.0 grams (0.23 mole) of sodium iodide in 100 milliliters of methyl ethyl ketone was refluxed on a steam bath for 24 hours. The salt cake which resulted was removed by filtration and the residue washed with fifty milliliters of methyl ethyl ketone. After combining the filtrate and wash, it was diluted to 500 milliliters with water, and extracted with three 150-milliliter portions of ether. The ethereal solution was washed with 100 milliliters of saturated sodium bicarbonate solution, 100 milliliters of ten percent aqueous sodium thiosulfate, and dried over magnesium sulfate. The ether was removed by distillation to yield 21 grams (51 percent of the theoretical yield) of a nearly colorless liquid, 2-iodoethyl 3-iodopropionate, having a boiling point of 100–109 degrees centigrade at one millimeter of mercury pressure absolute.

PREPARATION 2.—2-DIETHYLAMINOETHYL 3-DIETHYLAMINOPROPIONATE DIHYDROCHLORIDE

To a solution of 33 grams (0.093 mole) of 2-iodoethyl 3-iodopropionate in 200 milliliters of dry benzene was added 27.3 grams (0.373 mole) of diethylamine. This mixture was allowed to stand at room temperature for four days, cooled in an ice bath, and the crystals which formed were removed by filtration. The filtrate was concentrated to 100 milliliters on a steam bath, chilled in an ice bath, and the resulting precipitate removed by filtration. The filtrate was then treated with 10.9 grams (0.30 mole) of hydrogen chloride in 500 milliliters of acetone. The colorless solid which precipitated was removed by filtration and recrystallized twice in 125-milliliter portions of methanol. There was thus obtained 8.7 grams of 2-diethylaminoethyl 3-diethylaminopropionate dihydrochloride, melting at 221.5 degrees centigrade, when the rate of heating is one degree per minute from 215 degrees centigrade.

Calculated: $C_{15}H_{30}Cl_2N_2O_2$: C, 49.21; H, 9.53; Cl, 22.35. Found: C, 48.84; H, 9.10; Cl, 22.21.

The following examples illustrate procedures whereby the compounds of the present invention may be prepared, but are not to be construed as limiting the invention thereto.

Example 1

To a solution of 10.0 grams (0.028 mole) of 2-iodoethyl 3-iodopropionate in fifty milliliters of chloroform was added 5.0 grams (0.068 mole) of dimethylethylamine. This mixture was allowed to stand at room temperature for three days, and the excess chloroform decanted from the pale yellow oil which resulted. The oil was dissolved in 25 milliliters of refluxing methanol, and five milliliters of ether added. The mixture was placed in an ice chest. After three days, the colorless rosettes which formed were separated by filtration. After recrystallization there was thus obtained 4.6 grams of colorless crystals, 2-(dimethylaminoethylammonio)ethyl 3-(dimethylethylammonio)propionate diiodide, having a melting point of 177–179 degrees centigrade.

Analysis.—Calculated: $C_{15}H_{30}I_2N_2O_2H_2O$: C, 30.13; H, 6.22; I, 48.98. Found: C, 30.43; H, 5.29; I, 48.90.

In a manner similar to that of the foregoing Example 1, diethylmethylamine may be substituted for the dimethyl-

ethylamine to prepare 2-(diethylmethylammonio)ethyl 3-(diethylmethylammonio)propionate diiodide.

Example 2

A solution of 3.2 grams (0.010 mole) of 2-diethylaminoethyl 3-diethylaminopropionate dihydrochloride in twenty milliliters of water was treated with seven grams (0.05 mole) of potassium carbonate, and the oil which separated was extracted with three fifty-milliliter portions of ether. The combined ether extracts were dried over anhydrous sodium sulfate, filtered, and the ether evaporated. The resulting colorless oil was dissolved in 25 milliliters of acetone and six grams (0.04 mole) of methyl iodide added. After standing for one day at room temperature, crystals were obtained and these crystals removed by filtration. There was thus obtained 4.9 grams of colorless crystals, which after two recrystallizations from a mixture of methanol, acetone and ether, yielded dense colorless crystals, 2-(diethylmethylammonio)ethyl 3-(diethylmethylammonio)propionate diiodide, having a melting point of 184–185 degrees centigrade.

Analysis.—Calculated: $C_{15}H_{34}I_2N_2O_2$: C, 34.10; H, 6.49; I, 48.05. Found: C, 33.80; H, 6.44; I, 48.20.

In the manner of the foregoing examples, other compounds having different halogen anions may be prepared by substituting methylbromide or methylchloride for the methyl iodide of Example 2, or by bromine for the iodine contained in the starting material of Example 1. Alternatively, the iodide can be converted to the chloride or bromide by transhalogenation using ion exchange resins in conventional manner.

Example 3

A solution of one part of 2-(diethylmethylammonio)ethyl 3-(diethylmethylammonio)propionate diiodide in ten parts of water was treated with 0.65 part of silver nitrate in ten parts of water. The silver iodide which formed was removed by filtration, and the water removed from the filtrate by distillation under reduced pressure to yield a colorless glass-like solid. After recrystallizing from isopropanol, acetone, ether and two portions of isopropanol, there was obtained 2-(diethylmethylammonio)ethyl 3-(diethylmethylammonio)propionate dinitrate, as very hygroscopic colorless crystals, melting at 155 degrees centigrade.

Analysis.—Calculated for $C_{15}H_{34}N_4O_8H_2O$: C, 43.26; H, 8.71. Found: C, 43.8; H, 8.6.

Example 4

A solution of 2.5 parts of 2-(dimethylethylammonio)ethyl 3-(dimethylethylammonio)propionate diiodide in fifty parts of methanol was treated with 1.7 part of silver nitrate in fatty parts of methanol. The silver iodide which precipitated was removed by filtration and 200 parts of ether added to the filtrate, precipitating a colorless, viscous oil. This oil was separated and dissolved in refluxing isopropanol. Upon cooling, crystals formed, which were separated and recrystallized from isopropanol. There was thus obtained 2-(dimethylethylammonio)ethyl 3-(dimethylethylammonio)propionate dinitrate, as colorless crystals, melting at 162 degrees centigrade.

Analysis.—Calculated for $C_{15}H_{30}N_4O_8$: C, 42.15; H, 8.17. Found: C, 41.7; H, 7.9.

In a manner similar to that of the foregoing Examples 3 and 4, other anions, such as, for example, the sulfate, phosphate, acetate, et cetera, may be substituted for the halide or nitrate, by the procedure of the examples or by the use of ion exchange resins, in conventional manner.

It was very surprising that the compounds of the present invention have relatively little cholinergic activity, since closely related compounds, 2-(trimethylammonio)ethyl 3-(trimethylammonio)propionate diiodide or dichloride, possess considerable cholinergic effect.

This application is a continuation-in-part of our prior

filed application Serial No. 415,974, filed March 12, 1954, now abandoned.

Various modifications may be made in the compounds of the present invention without departing from the spirit or scope thereof, and it is to be understood that we limit ourselves only as defined in the appended claims.

We claim:

1. A compound having the formula:

wherein R and R' are selected from the group consisting of methyl and ethyl and wherein X and X' are stable non-toxic anions.

2. 2-(dimethylethylammonio)ethyl 3 - (dimethylethylammonio)propionate dihalide, wherein the halogen is selected from the group consisting of chlorine, bromine and iodine.

3. 2-(diethylmethylammonio)ethyl 3 - (diethylmethylammonio)propionate dihalide, wherein the halogen is selected from the group consisting of chlorine, bromine and iodine.

4. 2-(diethylmethylammonio)ethyl 3 - (diethylmethylammonio)propionate dinitrate.

5. 2-(dimethylethylammonio)ethyl 3 - (dimethylethylammonio)propionate dinitrate.

6. 2-(dimethylethylammonio)ethyl 3 - (dimethylethylammonio)propionate diiodide.

7. 2-(diethylmethylammonio)ethyl 3 - (diethylmethylammonio)propionate diiodide.
